UNITED STATES PATENT OFFICE.

WILLIAM KRAEDEMANN, OF SHEBOYGAN, WISCONSIN.

CUTTER FOR CHAIR-ARM BRACES.

No. 903,990.

Specification of Letters Patent.

Patented Nov. 17, 1908.

Application filed March 30, 1908. Serial No. 424,131.

To all whom it may concern:

Be it known that I, WILLIAM KRAEDEMANN, a citizen of the United States, residing at Sheboygan, in the county of Sheboygan and 5 State of Wisconsin, have invented a new and useful Cutter for Chair - Arm Braces, of which the following is a specification.

This invention relates to wood working machines, and more especially to that type 10 of wood working machine arranged to form the ends of chair arm braces.

One object of the invention is to provide a simple machine of the kind described, arranged to form the end of a chair arm brace 15 of various types and of various taper.

Another object of the invention is to provide a machine of the kind described in which it will be possible to adjust the arm for varying degrees of curvature.

20 With these and other objects in view, the invention consists in certain novel arrangements in detail, combination of parts, and specific forms of construction described in the specification, illustrated in the accompanying drawings, and set forth specifically in the claims.

In the accompanying drawings, like parts are indicated by similar characters of reference throughout the several views.

30 Figure 1 is a perspective view of the device as applied to a bench. Fig. 2 is a longitudinal sectional view therethrough. Fig. 3 is a transverse sectional view therethrough.

Similar numerals of reference are employed 35 to indicate corresponding parts throughout the several figures of the drawings.

The body 10 is provided with a longitudinal recess in the bottom thereof. At the 40 front of the recess 11 is held a plate 12 which extends across the bottom of said recess up the front of the machine, and back into a rabbeted portion 13. This plate is held to the body portion by screws or other suitable 45 means, as indicated at 14.

In the rabbeted portion 13 above the plate is held a cutting block 15. The plate is provided at its angled part with a slot 16 hereinafter described.

50 In the body 10 below the rabbeted portion 13 is formed a recess 17 and a slot 18 is formed in the plate opposite said recess. In this recess below the rabbeted portion is held an angle plate 19 normally pressed 55 to the upper end of the recess by means of a spring 20. On the front of the plate is

held an angle plate 21 provided with a knife edge 22. On this plate is secured the angle plate 19 by any suitable means, as by screws 23. In this angle plate is another angle 60 plate 24, provided at the upper end with lugs 25. A screw 26 provided with a thumb nut 27 is held in the angled portion of the plate 21, being prevented from longitudinal movement therethrough by means of a collar 28. The plate 24 is provided with an angled portion 29 having an internally 65 screw-threaded opening therein arranged to receive the screw 26. It will be observed that by means of this arrangement the angle 70 plates 24 and 21 may be adjusted relative to each other.

In the rear of the device at the top of the body portion 10 is formed a recess 30 which is covered by a plate 31 having a slot 32 cut 75 therethrough. A plate 33 is held at the rear end of the device and is provided with an opening 34 therethrough at the upper end thereof. A screw 35 passes through this opening, and rotates therein, being prevented from longitudinal movement by the collar 36. At the rear end of the screw 35 is mounted an operating crank 37. Upon the plate 31 is slidably mounted a plate 38 having rearwardly extending arms 39, which 80 are joined by a cross bar 40 provided with an internally threaded opening to receive the screw 35. The plate 38 is further provided with a threaded opening 41. The plate 38 is made in the form of a yoke having 85 arms 42 to embrace the sides of the body portion 10, and its arms are provided with slots 43 therein. The yoke 44 is held above this plate, the arms whereof extend downward into the slots 43 and this yoke is arranged to move longitudinally therein.

A screw 45 passes through this yoke and into the threaded opening 41 in the plate 38. Upon the lower end of this yoke are pivotally mounted arms 46 provided with 90 upwardly extending portions 47. The upwardly bent portions 47 are rigidly attached to a yoke 48 spaced therefrom at the lower attachment by the distance blocks 49. The upper attachments forms a pivotal support 95 wherein there is mounted a knife lever 50 comprising a pair of arms 51 and a handle 52. Adjustably attached to the arms 51 is a U shaped knife holder 53, by means of slots 54 formed in the arms 51 and a bolt 55 100 extending therethrough and into the U frame carrying the knife.

Mounted on the U-frame is a forming knife 56, being held therein by any preferred means, as by the bolt 57. The yoke 48 is provided with slots 58 therein, through 5 which extends a bar 59 having a cam 60 thereon. Fixed to the outer end of the bar 59 are levers 61. On the floor within easy reach of the operator's foot is a treadle or similar device connected to the levers 61 by 10 any suitable means, as by the loop and rod 62. It is not deemed necessary here to show this treadle, as the same forms no essential part of the device. In the yoke 48 is held a U-frame 63 arranged to receive the ends of 15 the bar 59, and having a thumb nut 64, so arranged that the distance between the U frame and the end of the yoke may be regulated, as desired. Oppositely disposed slots 65 extend through the side walls of the recess 11 and a bar 66 passes through the arms 42 and the slots 65, being arranged for longitudinal movement therein. Upon one end of this bar is mounted a ratchet 67 arranged to co-act with a pawl 68. The bar is further provided with a square or like device 20 for rotating the same, as indicated at 69. A U plate 70 is mounted on this bar to lie within the recess 11, and a roller 71 is held in the end of said U plate. A spring 72 lies 25 between the sides of said U plate.

Upon the bar 66 is mounted a roller 73 and a spring 72 is connected therewith by means of a suitable strap 74. The other end of the spring 72 is connected to a strap 30 which passes over the roller 71 and down through the slot 16, and is attached to the cam 50. It is obvious that the purpose of the square end of the bar and the ratchet and pawl is to properly tension the spring 40 72 as may be required.

In the operation of the device, a chair arm brace is placed beneath the knife, the end being forced firmly against the adjustable stop. The treadle is then depressed with the foot, 45 which causes the arm 61 to rotate, thus actuating the cam 60 and pulling the knife firmly down upon the chair arm brace. The handle 52 is then depressed. The stop plate being properly adjusted, the arms 51 of the 50 knife lever 50 will strike the lugs 25 just previously to the edge of the knife blade arriving at the knife edge 22 of the stop plate. The stop plate will then be depressed by means of the arms 52 and the knife will be 55 allowed to operate without at any time coming into contact with the upper end of said stop plate.

In continuing the operation, the foot is removed from the treadle and the cam is rotated to the position shown in Fig. 2 by 60 means of the spring 72. The spring at the same time keeps the cam and the parts attached thereto firmly against the body portion of the underside of the device. At the 65 same time that this occurs, the spring 20

forces the stop plate 21 back to its original position. The chair arm may then be removed from beneath the knife, and the operation repeated as desired. To adjust the knife above the body portion for varying 70 thicknesses of chair arm braces, it is only necessary to rotate the screw 64. By this means the knife may be raised or lowered to any required degree.

When it is desired to make a cut of long 75 radius on a chair arm brace the parts are adjusted as follows. The screws 55, are loosened and moved near the bottom of the slot 54. This of course raises the U frame higher with the knife blade. In order to 80 properly position the knife blade for the desired thickness of chair arm brace, the same is again lowered by means of the screw 45. Additional adjustment may be given by the screw 64, to effect this purpose. The 85 fulcrum being at a distance from the knife blade, the cut will be rendered one of long radius. If now it is desired to start the cut well back on the chair arm brace, the adjustment is obtained by means of the screw 35, 90 which moves the knife to or from the butt end of the machine. By means of this screw the proper length of the curved portion of the brace can be readily secured. Further adjustment of the beginning of the cut may 95 be made by proper manipulation of the screws 45 and 64. If it be desired to begin the cut abruptly the knife is tilted by means of the screw 45, and the adjustment to or from the base regulated by the screw 64. If, 100 again, it be desired to begin the curve tangent with the curve of the chair arm brace the screw 45 is so manipulated that the knife will lie parallel to the base, and the screw 64, moved to bring the same down smoothly on 105 the chair arm brace when in position for cutting.

What is claimed is:—

1. In a device of the character described, a base, a yoke plate slidably mounted longitudinally of said base, a pair of arms attached to said yoke plate, a lever fulcrumed on said arms, a knife adjustably mounted on said lever, a handle on said lever, and an adjustable stop. 110

2. In a device of the character described, a base, a yoke plate mounted for longitudinal movement on said base, a second yoke carried by said yoke plate and vertically adjustable thereon, arms attached to said second yoke, a knife lever pivotally mounted on said arms, a knife adjustably mounted on said lever, a handle on said lever to actuate the same, and an adjustable stop. 120

3. In a device of the character described, a base, a yoke plate loosely embracing the forward portion of said base, a lever connected to said yoke plate, and a knife adjustably mounted on said lever. 125

4. In a device of the character described, 130

4
arranged to normally hold said knife away from said base, a cam arranged to draw said knife toward said base against the action of said spring, a slotted yoke slidably mounted toward the rear of said base arranged for longitudinal movement thereof, means for moving said slotted yoke longitudinally of the base, a third yoke arranged for vertical movement in the slots of said second yoke, means for adjusting the relative positions of said slotted yoke and the third yoke, arms

rigidly attached to the first mentioned yoke, and a pivotal connection between the third yoke and said arms.

In testimony that I claim the foregoing 15 as my own, I have hereto affixed my signature in the presence of two witnesses.

WILLIAM KRAEDEMANN.
